Primary Examiner — Samantha Wood(74) *Attorney, Agent, or Firm* — Rabin & Berdo, P.C.**CLAIM**

The ornamental design for an air nozzle for hair dryer, as shown and described.

DESCRIPTION

FIG. 1 is a perspective view of an air nozzle for hair dryer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is an exploded view thereof.

The broken lines are included for the purpose of illustrating portions of the air nozzle that form no part of the claimed design.
